CHARGE FORMING DEVICE

Bernard C. Phillips, Toledo, Ohio, assignor to The Tillotson Manufacturing Company, Toledo, Ohio, a corporation of Ohio

Application February 6, 1950, Serial No. 142,630

8 Claims. (Cl. 261—41)

1

This invention relates to charge forming devices for use with internal combustion engines and more especially to a carburetor wherein the major operating components are mounted upon a carburetor body and relates to improvements upon the charge forming device disclosed in the application of Edward H. Foster Serial No. 104,225.

An object of the present invention is the provision of a carburetor wherein the fuel reservoir or chamber is made of sheet material and in which the valve mechanism controlling the fuel flow to the reservoir and the float mechanism for actuating the valve are mounted upon the carburetor body independently of the fuel reservoir construction.

Another object of the invention resides in the provision of a carburetor construction wherein the operative components of the carburetor are compactly arranged so as to minimize the space occupied by the carburetor as well as to reduce the cost of manufacturing the same.

Another object of the invention is the provision of a carburetor wherein the float controlled valve mechanism for regulating the flow of fuel into the float bowl or fuel reservoir is completely independent of the float bowl construction whereby the latter may be removed or assembled without disrupting the float controlled valve and associated elements.

Another object of the invention is the provision of a carburetor having a float bowl formed of comparatively thin sheet material such as brass, copper, aluminum or the like, which is secured to a carburetor body by simple means which may be readily manipulated to assemble or remove the float bowl with a minimum of effort and time.

Another object of the invention is the provision of a fuel metering means especially adaptable for incorporation in charge forming devices of a character in which the flow rate of fuel through the metering means is substantially unaffected throughout normal operative temperature ranges of fuel or by changes in viscosity of fuel within the range of usable fuels.

A further phase of the invention relates to the provision of a simple yet effective fuel metering means of the fixed orifice type, the member formed with the metering orifice being mounted in a manner to facilitate the ready interchange of members provided with orifices of different sizes for securing varying rates of fuel flow.

Further objects and advantages are within the scope of this invention such as relate to the arrangement, operation and function of the related

2

elements of the structure, to various details of construction and to combinations of parts, elements per se, and to economies of manufacture and numerous other features as will be apparent from a consideration of the specification and drawing of a form of the invention, which may be preferred, in which:

Figure 1 is a top plan view of a charge forming device or carburetor embodying the invention;

Figure 2 is a vertical longitudinal sectional view taken substantially on the line 2—2 of Figure 1;

Figure 3 is a vertical transverse sectional view taken substantially on the line 3—3 of Figure 1;

Figure 4 is an enlarged detail view showing a fuel metering means forming a part of the invention;

Figure 5 is a sectional view similar to Figure 2 illustrating a modified form of construction, and

Figure 6 is a view similar to Figure 5 showing a further form of construction.

Referring to the drawings in detail and first with respect to the form of the invention illustrated in Figures 1 through 4 inclusive, the carburetor includes a body member 10 formed with a mixing passage 11 having a venturi 12 in communication with an air inlet passage 14 connected by a tube 15 of an air cleaner (not shown). The mixing passage 11 is of smaller diameter than the air inlet 14, the axes of passage 11 and inlet 14 being eccentrically arranged, the axis of the mixing passage being nearer the fuel level in the receptacle 18. By this arrangement the fuel discharged into the venturi as hereinafter described is lifted but a small distance above the fuel level in the receptacle to the point of discharge.

A suitable fuel chamber or fuel reservoir 17 is provided for the carburetor and includes a bowl-like member or receptacle 18 formed of sheet material as for example brass, copper or any composition or alloy which is not subject to the corrosive effects of the fuel. As will be seen in Figure 2 the carburetor body 10 is formed with an annularly shaped groove 20 adapted to accommodate the rim or edge of the receptacle 18, a suitable sealing gasket 21 being disposed between the rim of the receptacle and the walls of the channel 20, in order to effect a fluid tight seal between these elements. While the receptacle 18 is illustrated as substantially semispherical in configuration, as this shape facilitates the formation of the receptacle from sheet metal, it is to be understood that a receptacle of different configuration may be utilized without departing from

the spirit of the invention. The carburetor body 10 is formed with a depending portion 23 which has a hollow interior forming a fuel well 24. The lower portion of the interior well thereof is threaded to receive a plug 26 which serves to close the lower end of the depending portion 23. The plug 26 is formed with a polygonally shaped head 27 which serves to secure the receptacle 18 in assembled relation with the body 10, an annular sealing gasket 28 being disposed between the head 27 and the receptacle 18 to provide a fluid tight seal. The bolt or plug 26 forms the sole means for securing the receptacle 18 in assembled relation with the carburetor body. The carburetor body 10 is formed with a fuel inlet passage 31 which includes a horizontal duct 32 and a vertical passage 33. The wall of the duct 32 is threaded as at 34 to accommodate a coupling with a fuel supply tube 36 in communication with a fuel supply. The vertical passage 33 of the fuel inlet is threaded as at 35 to receive and accommodate a fitting 36 the latter having an interior bore 37 terminating in a valve seat portion 38. A valve 39 of non-circular cross-section is slidably disposed in the bore 37 in fitting 36 and has a cone shaped or needle portion 40 cooperating with valve seat 38 in order to regulate or control the ingress of fuel into the float chamber 17.

The body portion 10 is formed with depending ears 42 which are bored to receive a pivot pin 43 adapted to support a bracket 44, one arm of which is secured as by soldering or other suitable means to a float 45 disposed in the float chamber or fuel reservoir 17. The float member 45 is preferably fabricated of two annularly shaped cup-like elements 47 and 48 which are joined together as by soldering, brazing or the like at their overlapping central portions to form an hermetically sealed construction. The bracket 44 is provided with an upwardly extending portion 49 which is adapted to engage the extremity of the valve member 39 as particularly shown in Figure 3. The float member 45 is thus articulately or pivotally connected to the ear portions 42 of the body member 10 and, through the medium of the bracket 44 engaging the valve member 39, controls or regulates the flow of fuel into the float chamber 17 through the inlet 31. As the float member 45 is elevated by reason of the fuel rising in the receptacle 17, pressure is exerted in an upward direction through the bracket 49 to move or bias the valve 39 toward closed position, that is, with the needle or tapered portion 40 engaging the valve seat 38 to interrupt the flow of fuel into the float chamber when the fuel therein reaches a predetermined level.

The mixing passage 11 is provided with a throttle valve in the form of a disc 52 which is mounted upon a transversely extending shaft 53 journaled in suitable boss portions 54 formed on the carburetor body 10. Manipulating means is provided for the throttle valve in the form of an arm 56 fixedly secured to one extremity of the shaft 53, a coil spring 57 surrounding a portion of the shaft 53 and being hooked over the arm 56 as shown at 58 in order to resiliently bias the valve 52 toward closed position. The arm 56 may be connected to a suitable operating rod 60 as shown in Figures 1 and 2.

A suitable valve in the form of a disc-like member 62 is mounted upon a transversely extending shaft 63 which is journaled in suitable boss portions 64 formed integrally with the body portion of the carburetor. One end of the shaft

63 may be bent laterally as at 65 to facilitate the manipulation of the valve 62 in order to control the admission of air to the carburetor through the air inlet passage 14. Frictional resistance is provided for the shaft 63 in order that the air valve may be retained in an adjusted position. This means is inclusive of a coil spring 67 which surrounds a portion of the shaft 63 and abuts against a disc or washer 68 held in place on the shaft by means of a pin 69. The passage 11 of the carburetor is in communication with an engine manifold 70 the manifold being secured to a flange portion 71 of the carburetor body by means of suitable bolts 72.

The upper extremity of the depending portion 23 forming the fuel well 24 is threaded as at 74 to receive a fitting 75 which is formed with an interior bore 76 the upper outlet of which forms a main fuel discharge orifice 78 into the mixing passage 11. The fuel discharge orifice preferably opens in the zone of the choke band 77 of the venturi 12, the choke band being the point or zone of greatest restriction to the flow of air through the carburetor. The maximum speed of air passing through the carburetor exists at the choke band 77 and the high air speed through the choke band facilitates the discharge of fuel from the orifice 78 into the mixing passage.

In some installations it is desirable to bleed air into the fuel at the time of its discharge through the main fuel orifice. To this end the carburetor is provided with an air bleed passage or channel 80 which establishes communication between the main air inlet 14 and the fuel well 24. The admission of air to the fuel well through the passage 80 provides for the admixing with the liquid fuel in the fuel well of a relatively small amount of air so that the fuel discharged through the main jet or orifice 78 and the main fuel orifice is in the form of an emulsion or admixture, that is, having small bubbles of air in the fuel.

The carburetor is provided with means for introducing fuel to the mixing passage for idling or slow speed engine operation when the throttle valve 52 is in closed or substantially closed position. Extending vertically of the carburetor in the embodiment illustrated as shown in Figure 2 is a relatively small tube 82 which depends below the fuel level in the receptacle 17 and extends upwardly terminating in a bore 84 in the carburetor body. The upper end of tube 82 extends into the hollow interior of a fitting 85 which is formed with openings 86 to facilitate fuel flow into the bore 84. The bore 84 is in communication with a chamber 87 by means of a duct or passage 88. The chamber 87 is in communication with the mixing passage 11 by means of orifices or ducts 89 and 90. As particularly shown in Figure 2, the orifice 89 is in communication with the mixing passage slightly in advance of the throttle valve 52 for engine idling operation while the fuel orifice 90 is in communication with the mixing passage slightly to the rear of the valve 52 when the latter is in closed position, and serves to supply fuel to the mixing passage when the throttle is partially opened and before the main fuel jet is caused to operate. The upper extremity of the chamber 87 is closed by means of a Welsh plug 92 and the upper end of the bore 84 is closed by means of a threaded plug 93 on fitting 85.

Means are provided for admitting air for admixing with the fuel supplied to the supplemental orifices 89 and 90 prior to the ejection of fuel therefrom into the mixing passage 11. A wall of

the air inlet passage 14 is provided with a duct 95, the amount of air admitted through the passage 95 being controlled by a valve 96 which is threaded as at 97 into a bore in a boss 98 formed on the carburetor body. A knurled manipulating portion 99 is formed on the valve 96 in order to facilitate manual control thereof. A spring 100 surrounds the threaded portion of the valve member 96 adjacent the manipulating portion 99 and serves to provide a frictional component to retain the valve 96 in adjusted position. A passage 101 establishes communication between the zone adjacent the valve 96 and the bore 84. In this manner a controlled amount of air may be admitted through the passages 95 and 101 to the bore 84 in which zone fuel flowing through the openings 86 is admixed with air in the bore 84, a mixture of fuel and air thereafter passing through the passage 88 and chamber 87 for discharge into the mixing passage 11 through the orifices or ducts 89 and 90.

The present invention is inclusive of novel means for metering or regulating the flow of liquid fuel from the fuel reservoir 17 into the fuel well 24. As shown in Figures 2, 3 and 4 a wall of the depending portion 23 is bored and threaded to receive a fitting or bushing 102. The bushing 102 is provided interiorly with a ledge 104 which positions a plate or cup-like member 105 in position in the fitting 102. The member 105 is pressed into or otherwise secured in the bore 103 in the fitting. The member 105 is made comparatively thin, a structural feature which I have found forms an important part in controlling the flow of fuel into the fuel well 24. The cup 105 is formed with a metering or passage orifice 106 which establishes communication between the reservoir 17 and the well 24. By making the plate or cup 105 relatively thin in dimension, the rate of fuel flow through the passage 106 will be substantially unaffected by variations in the viscosity of the fuel over a reasonable range suitable for use in internal combustion engines. For example, it is a conventional practice in the operation of two cycle engines to introduce a quantity of lubricating oil or lubricant into the liquid fuel in the supply tank for admixture with the fuel prior to its passage into the carburetor. As lubricating oil used for this purpose usually has a higher viscosity factor than the fuel, the viscosity of fuel and oil mixture is higher than the fuel alone. Irrespective of whether the fuel passes through the carburetor with or without lubricating oil being admixed therewith, the flow rate through the metering orifice 106 remains substantially constant. In order to obtain this result of uniform flow rate through the orifice 106, the plate 105 may be made of a thickness up to approximately thirty-five thousandths of an inch without materially affecting the rate of fuel flow through the plate. It has been found that plates of a thicker dimension do not function satisfactorily with varying viscosity factors of fuel and lubricant mixture. Through the utilization of a thin plate and orifice construction of the character illustrated in Figure 4, there is provided a simple yet effective means for establishing a substantially uniform flow rate from the receptacle 17 into the well irrespective of the viscosity of the liquid passing therethrough within the range of usable fuel mixtures for engines with which the carburetor may be utilized. I have found by actual and exhaustive tests that this desirable result is obtainable with the above described construction.

Venting means is provided for the chamber 17

in order to prevent air lock or unequal pressure such as would interfere with flow into and out of the chamber. As illustrated in Figure 3, a vent opening 108 is provided to the atmosphere so as to establish an equalized pressure in the fuel chamber 17.

The operation of this form of the invention is as follows:

Fuel is introduced into the inlet passage 31 from a fuel supply (not shown), the fuel flowing past the polygonally shaped valve member 39 through the bore 37 into the fuel chamber 17. As the fuel level rises in the chamber 17 the float 45 is buoyed upwardly and being pivoted for movement around the axis of the pin 43, the portion 49 of bracket 44 urges the valve member 39 upwardly. When the float has been elevated a predetermined distance in order to establish a definite fuel level in the chamber 17, the pressure of arm 49 moves the valve 39 to closed position to interrupt fuel flow into the chamber 17. When the internal combustion engine with which the carburetor may be used is started, the air or choke valve 62 is preferably closed or nearly closed in order to establish a proportionately high vacuum to insure fuel flow into the engine for starting purposes. After the engine is started, the air valve 62 is moved to full open position as indicated in full lines in Figure 2. During idling operations of the engine, the throttle valve 52 is in closed position as shown in Figure 2 or near closed position. During idling operations of the engine under the influence of subatmospheric pressure developed by the engine, fuel is taken upwardly through the tube 82 from the well 24 where it is mixed with air in the bore 84, the air for mixing with the fuel being taken in through the passages 95 and 101. The fuel and air mixture is then conveyed through the duct 88 and bore 87 for discharge into the mixing passage 11 through the orifices 89 and 90. When the valve is in full closed position as indicated in Figure 2, fuel is taken into the passage through the orifice 89 in advance of the valve disc 52 to provide an idling mixture for the engine. When the valve 52 is partially opened and before fuel is delivered into the venturi 12 from the main fuel orifice 78, the orifice 90 delivers additional fuel and air mixture into the mixing passage. The valve disc or throttle valve 52 is provided with openings 55 in order to permit the passage of some air through the carburetor for admixing with the fuel and air mixture discharged through the orifice 89 when the throttle valve 52 is in full closed position. As the throttle 52 is moved to an open position to increase the speed of the engine, air passes through the venturi at a much higher rate of speed as the engine speed increases by reason of the decrease in pressure in the mixing passage. This increase in air speed through the venturi 12 exerts a lifting force on fuel in the well 24 whereby fuel is extruded from the main fuel orifice 78 into the choke band 77 of the venturi. When the main fuel jet 78 comes into operation, the fuel discharge from orifices 89 and 90 ceases and the fuel mixture passing into the engine is obtained entirely from the air passing through the venturi of the carburetor which is mixed with fuel from the main jet 78. During high speed operation of the engine, air is bled into the fuel in well 24 through the air bleed channel or duct 80 so that an emulsion or admixture of fuel and air is discharged into the venturi through the orifice 78. The metering orifice 106 establishes a uniform flow rate of fuel from the chamber 17 into the

well 24 so as to establish a predetermined maximum for fuel flow from the well 24 through the main discharge orifice into the mixing passage.

A modified form of fuel metering means for establishing a predetermined maximum flow of fuel from the chamber 17 to the fuel well is illustrated in Figure 5. In this form of construction the depending portion 23' of the carburetor body 10' is interiorly threaded as at 110 to receive the threaded portion of a fitting 111. The fitting 111 is formed with an interior bore 112 in which is disposed a needle valve 114, the extremity of the valve 114 cooperating with a restricted opening 115 in the fitting 111 for regulating the flow of fuel to the passage or duct 115. The bore 112 is in communication with the fuel reservoir or chamber 17 through the medium of a transversely extending passage 116 formed in the fitting 111. The needle valve 114 is formed with an enlarged portion 117 which is threaded into a threaded portion 118 in the fitting 111, the portion 117 being provided with a manipulating handle or pin 119 as shown in Figure 5. Thus the position of the valve 114 may be regulated by rotation of the valve through manual operation of the pin 119, the position of the valve 114 in the orifice 115 determining the metering or rate of fuel flow into the well 24.

A stuffing gland 120 is provided surrounding the portion 117 of the valve construction and cooperates with a threaded cup 121 so as to prevent leakage of fuel to the exterior of the receptacle 18 along the valve member 117. The fitting 111 serves a dual purpose, it encloses and supports the needle valve 114 and also secures the receptacle 18 in position. As shown a gasket 123 is disposed between a ledge portion 124 of the fitting 111 so that when the fitting 111 is threaded into the depending portion 23' of the carburetor body, the gasket 123 is brought into sealing engagement with the receptacle 18 to hold the latter into sealing contact with the gasket 21 in the channel 28 of the carburetor body 10'. By this means the metering of fuel may be accomplished by manipulating the needle valve 114, the fitting supporting the valve also functioning as a means for securing the receptacle 18 to the carburetor body. The operation and functioning of the carburetor illustrated in Figure 5 is the same as that hereinbefore described in connection with the form of the invention illustrated in Figures 1 through 3 inclusive.

Figure 6 illustrates a further form of the invention in which the carburetor body 10'' is provided with a depending central portion 23''. The depending portion 23'' is provided with a central bore 130 in which is disposed the fitting 75'', the latter being provided with an interior bore 131 the upper exit of which forms the main fuel extruding jet or orifice into the venturi 12''. The lower portion of the walls of bore 130 are threaded to receive a threaded portion 132 integrally formed on the fitting 75''. The portion 132 of the fitting is formed with a restricted opening 133 into which extends the tapered extremity 134 of a needle valve 135. The diameter of opening 133 is such as to cooperate with the tapered portion 134 of the metering valve or needle so as to regulate the flow of fuel from the float chamber 17 into the well or bore 131. The space 136 immediately beneath the portion 132 is in communication with the fuel supply chamber 17 by means of a passage or duct 137. The metering needle or valve 135 is made of hollow or tubular configuration having openings 139 in the side walls thereof so as to

permit the passage of fuel from the fuel well 131 to the interior of the tubular needle valve 135. The upper end of the valve extends into a fitting 140 which is disposed in a bore 84'', a passage 141 being in communication with the interior of the tube 135 and the bore 84''. The bore 84'' provides a mixing zone in which air is mixed with fuel passing upwardly through the valve tube 135 to supply a fuel and air mixture to the orifices 89'' and 90'' for idling or slow speed engine operation. The fitting 140 is fixedly connected to the tube 135 and is adapted to be manipulated by a handle 143 in order to regulate the position of the needle with respect to the metering orifice or bore 133 in portion 132. By this means rotation of the needle 135 and fitting 140 adjusts the position of the tapered portion 134 thereof in the orifice 133 to meter or control the flow of fuel from the chamber 17 through passage 137, space 136, orifice 133 and into the well 131. When the engine is idling, fuel from the well 131 flows through the openings 139 to the interior of tube 135, thence upwardly through passage 141 into the zone or space 84'' where the fuel is mixed with air from the passages 95'' and 101'' for subsequent discharge into the mixing passage 11'' through the orifices 89'' and 90''. An air channel or duct 80'' is provided for bleeding air into the bore 130 and through transverse openings 145 formed in the walls of the fitting 75'' into the well 131. In this manner a small amount of air is mixed with the fuel prior to its ejection from the main fuel orifice into the venturi 12''. In this form of construction receptacle 18 is held in place with respect to the body portion 16'' of the carburetor by means of a bolt 147 threaded into the interior of the depending portion 23''. A gasket 148 is disposed between the head of the bolt 147 and the receptacle 18 in order to make a fluid tight seal and prevent leakage of fuel from chamber 17.

In all forms of the invention, the tube for conveying fuel from the fuel well to the idling discharge ports extends through the main fuel jet and is disposed eccentrically therein, the tube being nearer to the air inlet so that fuel is discharged into the mixing passage from the main jet at the right side of the tube as viewed in Figures 2, 5 and 6.

It should be further noted that in all forms of the invention the float 45 is pivotally connected and supported from the body portion of the carburetor. By this means the receptacle 18 can be quickly and easily removed from the carburetor body for purposes of cleaning or inspection without dismantling or disassembling any of the other elements of the construction. In the form shown in Figure 1 removing the bolt 26 releases the receptacle from engagement with the body 10 without disrupting any of the other elements of the carburetor. In the form shown in Figure 5 the fitting 111 may be removed by rotating the same in a direction to disengage the threads with the threaded interior of the depending portion 23' thus permitting removal of the receptacle 18. In the form shown in Figure 6 removing the bolt 147 permits the receptacle 18 to be disengaged from the body portion 16'' of the carburetor. Through the arrangement of the present invention I have been able to provide an inexpensive receptacle assembly for a carburetor providing a fuel supply chamber or float bowl which may be easily manufactured and which is capable of quick assembly without the use of special tools.

It is to be understood that the valve 96 for regulating the amount of air for the idling mixture may, if desired, be disposed in a horizontal position i. e. in alignment with the axis of the channel or passage 101. This arrangement of control may be desirable when the carburetor is used with marine engines, and especially those of the so called "outboard" type embodying panel mounting for the carburetor and engine controls.

It is apparent that, within the scope of the invention, modifications and different arrangements may be made other than is herein disclosed, and the present disclosure is illustrative merely, the invention comprehending all variations thereof.

What I claim is:

1. In a charge forming device, in combination, a substantially horizontal body member, a receptacle secured to said body member forming a fuel chamber, a mixture outlet formed in said body member, a venturi formed in said body member axially aligned with the mixture outlet, an air inlet in line with said venturi and mixture outlet and formed in said body member, said body member having a portion depending into the receptacle formed with a fuel well beneath said venturi, said fuel well having an opening into said venturi, a secondary fuel-air mixture discharge orifice in a wall of said mixture outlet above said venturi, a secondary air inlet in a wall of said air inlet above said venturi and arranged to admit air for admixing with fuel prior to its discharge from said secondary orifice, a mixing chamber formed in said body member and located above said venturi, two passageways one of which connects said mixing chamber with said secondary air inlet and the other of which connects said mixing chamber with said secondary mixture orifice, said passageways being substantially parallel to said air inlet and mixture outlet, a fuel line connecting said well with said mixing chamber, means for metering fuel flow from said fuel chamber to said fuel well, and means formed in said body for admitting air into the well for admixing with the fuel prior to the discharge thereof into the venturi.

2. In a charge forming device, in combination, a substantially horizontal body member, a receptacle formed of sheet metal secured to said body member forming a fuel chamber, a mixture outlet formed in said body member, a venturi formed in said body member axially aligned with the mixture outlet, an air inlet in line with said venturi, and mixture outlet and formed in said body member, the axis of the venturi and mixture outlet being nearer the fuel level in said fuel chamber than the axis of the air inlet, said body member having a portion depending into the receptacle formed with a fuel well beneath said venturi, said fuel well having an opening into said venturi, a fitting in said opening projecting slightly into said venturi and having a main orifice for discharging fuel from said well into said venturi, a secondary fuel-air mixture discharge orifice in a wall of said mixture outlet above said venturi, a secondary air inlet in a wall of said air inlet above said venturi and arranged to admit air for admixing with fuel prior to its discharge from said secondary orifice, a mixing chamber formed in said body member and located above said venturi, two parallel passageways one of which connects said mixing chamber with said

secondary air inlet and the other of which connects said mixing chamber with said secondary mixture orifice, said passageways being substantially parallel to said air inlet and mixture outlet, a fuel line connecting said well with said mixing chamber and passing through said fitting, said main orifice, and said venturi, means for metering fuel flow from said fuel chamber to said fuel well, and means formed in said body for admitting air into the well for admixing with the fuel prior to the discharge thereof into the venturi.

3. In a charge forming device according to claim 2 and having removable means passing through an opening in the receptacle and engageable with the body member for securing the receptacle to the body member.

4. In a charge forming device according to claim 1 and having a fitting connected to said depending portion of said body member and having a passage therein for admitting fuel from the fuel chamber for discharge into the venturi, an adjustable valve in said passage having a portion accessible exteriorly of the receptacle for manipulating said valve, said fitting being formed to secure said receptacle to said body member.

5. In a charge forming device according to claim 1 and having said fuel metering means including a relatively thin member having a port therein for predetermined the fuel flow from the fuel chamber into the fuel well.

6. In a charge forming device according to claim 1 and having said fuel metering means including a fitting removably disposed in said fuel well, said fitting having a passage formed therein, a relatively thin metal plate extending across said passage, and a fuel metering port formed in said plate for establishing communication between said fuel chamber and said well.

7. In a charge forming device according to claim 1 and having said fuel metering means including a bushing removably disposed in said fuel well, a plate carried by said bushing, the thickness of said plate not exceeding thirty-five thousandths of an inch, and a fuel passage formed in said plate for establishing communication between said fuel chamber and said well.

8. In a charge forming device according to claim 1 and having a fitting connected to said depending portion of said body member and having a passage therein for admitting fuel from the fuel chamber for discharge into the venturi, an adjustable valve in said passage operated from above said venturi and being accessible exteriorly of said body member for manipulating said valve.

BERNARD C. PHILLIPS.
